UNITED STATES PATENT OFFICE.

ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

1,417,405.

Specification of Letters Patent. Patented May 23, 1922.

Application filed January 15, 1920. Serial No. 351,661.

To all whom it may concern:

Be it known that I, ARVID H. NERO, a citizen of the United States of America, and residing at New Britain, in the county of 5 Hartford and State of Connecticut, have invented certain new and useful Improvements in Electric Switches, of which the following is a specification.

My invention relates to electric switches, 10 and particularly to switches of the toggle type, the object of my invention being to provide a construction of simple and compact form adapted to afford a wide break on the actuation of the mechanism.

15 In the accompanying drawings.

Fig. 1 is a plan view of a switch in which my invention is embodied in one form;

20 Figs. 2 and 3 are longitudinal and transverse cross sections on the lines 2—2 and 3—3, Fig. 1, respectively; and

Fig. 4 is a detached perspective of the switch mechanism and frame.

As here shown the switch comprises an insulating casing 5 of inverted cup shape 25 adapted to be mounted in an outlet box by means of the ear pieces 6 and 7 secured at opposite ends of the casing by screws 8. The usual binding screw terminals 9, 10, 11 and 12 lie in channels 13 extending to the 30 opposite ends of the casing, and through which the main and branch wires are led to the binding screws. The switch terminals 14 and 15 underlie the binding screw terminals, but within the switch chamber, and 35 are integral with standards 16 and 17, which have offset foot pieces 18 and 19 into which the several binding screws respectively take to establish electrical connection with the lead wires. Additional securing screws 20 pass through the casing to aid in holding the 40 terminal foot pieces rigidly in position.

The switch mechanism is carried by a U-shaped frame 21, the side members of which have lugs 22 passed through slots in the 45 brackets 23 and secured thereto by spreading the lug ends after the fashion of a rivet. The brackets are in turn supported upon the insulating casing 5 by means of screws 24 passing therethrough and taking into offset 50 lugs at the base of the brackets.

The switch mechanism proper comprises a forked operating lever 25 pivoted on the pin 26 in the up-standing ears 27 of the frame, and passing out of the switch chamber through the slot 28 in the closed top

thereof. An operating handle 29 is secured in any suitable way to the bridge 30, which unites the legs of the operating lever. Straddled by the latter is a U-shaped rocker 31, the legs of which are notched at their free 60 ends and pivoted on lugs 32 struck inward from the side plates of the frame 21. The legs of the rocker 31 are slotted at 33 to receive the lugs 34 offset from the lower end of the lever 25 and working therein. These slots are extended into the bridge of the rocker but leave a cross web 35 to which one end of the switch spring 36 is engaged. The other end of this spring engages an anchor T-piece 37 passed through a hole in the 70 bridge 38 of the switch bar yoke 39. The latter straddles the frame 21, to which it is pivoted by means of bowed straps 40 slotted at 41 to receive the out-turned lugs 42 on the frame. The switch bars 43, which make and 75 break contact with the switch terminals 14 and 15, are carried by yokes 39 through suitable insulating connections. The throw of the yoke is limited by the impingement of its bridge piece 38 against the sides of the 80 aperture 44 in the base of the frame in which it works. It will be noted that the switch spring 36, which is always under tension, serves to maintain both the rocker and the switch yoke seated against their pivot lugs 85 on the frame.

The switch chamber is closed, after the assembly of the switch on the casing, by means of a metal cover 45 which is held to a marginal ledge 46 on the casing wall by the 90 screw bolts 8. An insulating lining 47 of paper, fiber or the like, may be utilized to face the metal plate.

The operation of the switch is readily understood. Assuming the parts to be in the position shown in Fig. 2, in which the switch bar connects the terminals 14 and 15, the switch lever 25 is swung on its pivot 26 by shifting the handle 29 to the right. As it swings, its lugs 34, engaging the rocker 100 31, swing the latter on its pivot 32 until the upper end of the switch spring 36 moves past the axis of oscillation 42 of the switch bar, whereupon the spring, further tensioned by this movement, exerts its effort to throw 105 the switch bar in the opposite direction with a snap action, thereby breaking the circuit at the terminals 14 and 15.

Various modifications in detail of construction will readily occur to those dealing 110

with the subject, and I do not limit my claim of invention to the precise construction shown. The construction illustrated, however, possesses the merit of economical manufacture of the metal parts, facile assembly, and a quick wide break at the switch terminals.

I claim as my invention—

1. In a snap switch mechanism, a pivoted lever with inwardly offset lugs at its inner end, a pivoted rocker slotted to receive said lugs, a pivoted switch yoke and an actuating spring operatively connected between said rocker and switch yoke.
2. In an electric switch, a U-shaped frame having inwardly and outwardly struck bearing lugs on its side plates, a rocker yoke lying between said side plates and pivoted on the inwardly struck lugs thereof, a switch yoke straddling the frame and pivoted on the outwardly struck lugs of the side plates, together with a switch spring operatively connecting said rocker and switch yokes.
3. In an electric switch, a U-shaped frame having inwardly and outwardly struck bearing lugs on its side plates, a rocker yoke lying between said side plates and pivoted

on the inwardly struck lugs thereof, a switch yoke straddling the frame and pivoted on the outwardly struck lugs of the side plates, together with a switch spring operatively connecting said rocker and switch yokes, the bearings in said rocker and switch yokes being open notches, and the switch spring serving to maintain the same seated against their respective bearing lugs.

4. In an electric switch, an insulating body of inverted cup shape, channelled at its closed end, a binding screw terminal plate lying freely in said channel, a switch terminal arranged within the chamber of the insulating body and having a tapped base, in combination with a binding screw passing through said terminal plate and the closed end of the insulating body and screwing into the tapped base of the switch terminal to establish electrical connection therewith and to maintain the binding terminal plate in position on the base, substantially as described.

In testimony whereof I have signed my name to this specification.

ARVID H. NERO.
